UNITED STATES PATENT OFFICE.

HENRY THOMAS HENDERSON, OF KEOKUK, IOWA.

IMPROVEMENT IN LOOM-PICKING MECHANISMS.

Specification forming part of Letters Patent No. **130,636**, dated August 20, 1872.

To all whom it may concern:

I, HENRY THOMAS HENDERSON, of Keokuk, Iowa, have made a new and useful Improvement in Looms, of which the following is a specification.

This invention relates to hand or power looms. The improved loom is made as set forth, referring to the accompanying drawing, in which—

Figure is a sectional elevation of the loom. Fig. 2 shows the joining of part of frame. Fig. 3 represents the shuttle-actuating mechanism.

The general structure and relations of the parts are shown in the drawing, and need not be fully detailed.

The batten G is pivoted to the frame A at G', and in its center portion bears the device for driving the shuttle. This consists of the pulley H pivoted to the batten G, and having an arm, H¹, connected by the cords H² and H³ to the pickers. To the pulley part H is fastened a strap, I, attached at the other end to an arm, I¹, projecting forward from the upright post I², which is pivoted at I³ to the cross-piece D. When the batten G is pushed backward the arm I¹ passes on one side of pulley H, and turns it on its pivot, by this means moving arm H¹ to the other side, and causing the shuttle to be thrown to that side. An elastic cord, K, connects the end of the arm H¹ with the upright I², so that when arm H¹

is at one side and arm I¹ is released by the forward motion of the batten G, the part I² is drawn to the same side, so that the arm I¹ passes the next time to that side of H. By this means a regular alternate motion is given the shuttle from side to side. The pulley H is pivoted to the batten so as to act as an eccentric, and as the strap I winds from it, it will move with increasing speed, thus giving an increasing speed to the shuttle-driver and the shuttle. The rod W, which connects the breast-beam B' to the upright I² to support it, is loosely pivoted at each end to allow the part I² to move sidewise on the pivot I³.

The loom is operated by hand on the top of batten G, or otherwise.

I claim—

1. The combination of the batten G, the pulley H, the arm H¹, the strap I, the arm I¹, the upright I², and the cord K, all arranged and operating as and for the purpose set forth.

2. The combination of the eccentric pulley H, the strap I, and the arm I¹, all arranged and operating as and for the purpose set forth.

HENRY THOMAS HENDERSON.
